The ornamental design for a tire, as shown and described.

DESCRIPTION

FIG. 1 is a perspective view of a tire showing our new design;

FIG. 2 is a front view thereof;

FIG. 3 is a rear view thereof;

FIG. 4 is a top plan view thereof, the bottom plan view being the same;

FIG. 5 is a right side view thereof;

FIG. 6 is a left side view thereof;

FIG. 7 is an enlarged view of the portion 7-7 in FIG. 2; and, FIG. 8 is a cross-sectional view taken along line 8'-8' in FIG. 7 to line 8-8 in FIG. 5.

In the drawings, the broken lines showing portions of the sidewall and inner bead depict portions of the tire that form no part of the claimed design.

It being understood that the outermost broken line in FIGS. 1, 5 & 6, represents the claim boundary.
